UNITED STATES PATENT OFFICE.

ELEAZER KEMPSHALL, OF SHARON, ASSIGNOR TO THEOPHILUS KING,
TRUSTEE, OF BOSTON, MASSACHUSETTS.

DESIGN FOR AN EYELET.

SPECIFICATION forming part of Design No. 24,867, dated November 12, 1895.

Application filed September 9, 1895. Serial No. 562,006. Term of patent 14 years.

To all whom it may concern:

Be it known that I, ELEAZER KEMPSHALL, of Sharon, in the county of Norfolk and State of Massachusetts, have invented and produced a certain new and original Design for Eyelets, of which the following is a specification, reference being had to the accompanying drawings, forming a part thereof.

This invention relates to a new and original design for eyelets; and it consists in the novel features of shape and configuration herein-after fully described, and claimed, and clearly illustrated in the drawings.

Figure 1 is a perspective view showing my design. Fig. 2 is a vertical sectional view thereof.

The essential feature of my design consists in a tubular-shaped body terminating in a head on top of and surrounding said body, having in cross-section the general shape of a semicircles with the diameter thereof at right angles with the sides of said body, the inner

surface of said head forming an unbroken continuation of the inner walls of said body.

a represents the tubular-shaped body of the eyelet, and *b* the head thereof. This head has in cross-section the general shape of a semicircle whose diameter is arranged at right angles to the body of the eyelet. The inner surface *b'* of this head forms, as shown, an unbroken continuation of the inner surface *a'* of the eyelet, thus presenting to the eye a ring merging into a cylinder.

I claim—

The design for an eyelet, substantially as shown and described.

In testimony whereof I have signed my name to this specification, in the presence of two subscribing witnesses, this 22d day of August, A. D. 1895.

ELEAZER KEMPSHALL.
